O. WILSON

SWITCH STAND

Filed Feb. 9, 1925

INVENTOR

Oliver Wilson

BY James N. Ramsey

ATTORNEY

UNITED STATES PATENT OFFICE.

OLIVER WILSON, OF COVINGTON, KENTUCKY.

SWITCH STAND.

Application filed February 9, 1925. Serial No. 7,839.

To all whom it may concern:

Be it known that I, OLIVER WILSON, a citizen of the United States, residing at Covington, in the county of Kenton and State of Kentucky, have invented certain new and useful Improvements in Switch Stands, of which the following is a specification.

My invention relates to means for throwing the switch stand into open and closed 10 positions, respectively.

The object of my invention is to provide simple, convenient, efficient, economical, easy and durable means for operating the switch stand in a confined space and to throw the 15 switch points into either open or closed position.

Another object of my invention is the construction of such a device that will remain automatically locked from the rail and that 20 the device, when the throwing lever is in either of its horizontal positions will render unnecessary the use of locks or latches. Locks or latches must be used on practically all types of switch stands now in general 25 use.

Another object of my invention is to provide a switch stand in which the number of the parts are reduced to a minimum.

A further object of my invention is to provide a switch stand which will be so constructed as to operate under all conditions of weather and which will never be clogged by snow or ice.

My invention consists in the parts and in 35 the construction, combination, location and arrangement of parts, as herein set forth and claimed.

In the drawings:

Fig. 1 is a side view of my invention;

Fig. 2 is a vertical cross section taken on a plane corresponding to line 2—2 of Fig. 1;

Fig. 3 is a perspective view omitting the base and cap;

Fig. 4 is a plan view of Fig. 3 showing 45 the mechanism with the throwing lever to the left;

Fig. 5 is a plan view of Fig. 3;

Fig. 6 is a similar view to Fig. 4 showing 50 the hand throwing lever to the right, as shown in Fig. 1;

Fig. 7 is a detailed view of the swivel block; and

Fig. 8 is a side elevation thereof.

In the embodiment of my invention, as illustrated, and which shows a preferred construction, I provide a switch stand 1, as shown in Fig. 1, which is adapted to be supported on the usual ties 2 and secured thereon by the usual method, as for instance, by spikes 3. For convenience in assembling 60 the working parts within the housing 4, said housing is made of two halves comprising base 5 and cap 6. As shown in Fig. 1, base 5 and cap 6 (after having the working parts assembled therein) are firmly held together 65 by bolts 7 and nuts 8. Hand throwing lever 9 is secured to the outer end 10 of crank shaft 11 by pins 12 and 13. Crank shaft 11 is journaled in bushing 14 which is inserted in hole 15 of boss 16, the upper half of said 70 boss being formed by cap 6 and the lower half of said boss being formed by base 5. Ribs 17 and 18, respectively, of cap 6 and base 5 are for the purpose of strengthening boss 16. Crank shaft 11, substantially as 75 shown, is provided with reduced end 19 which receives roller 20, said roller being rotatably secured on said reduced end 19 by washer 21 and spring cotter 22. Roller 20 is received in opening 23 of swivel block 24, as clearly shown in Fig. 3 and the movement therein will be described hereafter. Swivel block 24 has journals 24' which are pivotally received and supported by arm 25 integral with the upper swivel block bracket 27 and 80 arm 26 integral with the lower swivel block bracket 28. Said upper and lower swivel block brackets 27 and 28 have holes 29 and 30, respectively, in their vertical portions 31 and 32 for the purpose of receiving vertical 85 signal operating switch shaft 33. Said brackets 27 and 28 are securely fixed to said shaft 33 by pins 34 and 35. In addition to pins 34 and 35 the brackets 27 and 28, respectively, are protected from movement on 90 shaft 33 by dovetail connection 36. The swivel block brackets 27 and 28 are intermediate cap 6 and base 5 and are pivotally retained in this relation to said cap and said base by shaft 33 which extends through 95 100

bearing 37 in said cap 6 and bearing 38 in base 5 in which the extended shank 39 of lower swivel block bracket 28 is journaled. The upper end of shaft 33 may be provided 5 with the usual target and lantern support (not shown) of the present and well known construction. The extended shank 39 of lower swivel block bracket 28 has dovetail connection 40 with stud 41, said stud being 10 integral with connecting rod arm 42 and said arm 42 is retained on the lower end of shaft 33 by washer 43 and nut 44 which is screwed onto threads 45 of shaft 33. The connecting rod 46 (shown in dotted lines in 15 Figs. 3, 4, 5 and 6, respectively,) is connected to the switch points in the usual manner.

In Figs. 1 and 6 I have shown the hand throwing lever in position to the right which 20 we will assume closes the switch points. When in this condition and with my construction it is practically impossible to move the switch points by vibration of the rails or in any way except by shifting manually the hand throwing lever. The lower surface of the swivel block adjacent the crank shaft is preferably beveled downwardly toward said crank shaft in order to furnish as wide a bearing as possible for the 25 roller which engages the elongated slot. This results in easier operation than otherwise.

My novel switch operating means are very 30 simple, easily operated and efficient at all times and under all conditions of weather.

To open the switch merely throw hand throwing lever from the position illustrated in Figs. 1 and 6 until it assumes the position indicated by Fig. 4. Figs. 2, 3 and 5 40 show the switch in a neutral position. When the hand throwing lever is in the position shown in Fig. 4, the switch points are opened. To close the switch points raise hand throwing lever, which in turn, raises 45 crank shaft 11 and roller 20. Said roller operating in opening 23 of swivel block 24 moves said swivel block and the journals 24' of said swivel block being pivoted in the arms 25 and 26 of the upper and lower 50 swivel block brackets 27 and 28, respectively, impart motion to shaft 33, which in turn, impart motion to connecting rod arm 42. The connecting rod (shown in dotted lines) 55 being pivotally connected to said connecting rod arm, imparts motion to the switch points, thereby closing or opening them according to the position of the hand throwing lever.

Advantages of my invention are that it 60 dispenses with all gearing and the life of the device is much longer than otherwise; also it dispenses with the necessity of any latch to hold the throwing lever from rebounding out of position when the switch points are in closed position, by the vibra-

tion caused by the train passing the switch stand, thereby insuring absolute safety in the operation of my novel mechanism.

While I have chosen to illustrate the form and construction of my invention by the drawings herein and explanations of the same, I desire to emphasize the fact that the various forms and explanations relating thereto are not intended to include all of the structure in which my invention may be 75 incorporated. It is understood that my invention resides in the combination and arrangement of parts and in the details of construction as herein explained and that changes in the precise embodiment of the 80 invention, as herein disclosed, can be made within the scope of what is claimed without departing from the spirit of the invention.

What I claim as new and desire to secure by Letters Patent is:

1. In switch operating means, a housing, a vertical shaft journaled therein, a connecting rod arm fixed to said shaft, a switch point connecting rod pivotally attached to said arm and adapted to be operatively connected to the switch points, a yoke fixed to said shaft, a swivel block having an elongated slot or opening therein and pivotally mounted in said yoke, a pivotally mounted crank shaft having one end engaging the 95 walls of said opening, and a switch throwing arm mounted on the other end of said crank shaft.

2. In switch operating means, a housing, a vertical shaft journaled therein, an arm 100 fixed to said vertical shaft, a switch point connecting rod pivoted to said arm, a yoke fixed to said vertical shaft, a swivel block mounted in said yoke and having a vertical slot therein, a crank shaft suitably journaled and having one end mounted in said swivel block, and a switch throwing lever mounted on the other end of said crank shaft whereby said arm may be moved in reverse directions to operate said switch 110 points.

3. In switch operating means, a housing, a vertical shaft journaled therein, an arm fixed to said vertical shaft, a switch point connecting rod pivoted to said arm, a yoke 115 fixed to said vertical shaft, a swivel block mounted in said yoke and having a vertical slot therein, a crank shaft suitably journaled and having one end mounted in said swivel block, a roller mounted on said crank shaft within said swivel block and adapted to engage the walls of said vertical slot and a switch throwing lever mounted on the other end of said crank shaft whereby said arms may be moved in reverse directions to 120 operate the switch points.

4. In switch operating means, a housing, a vertical shaft journaled therein and having a yoke fixed thereto within said housing, a connecting arm fixed to said vertical shaft 130

and adapted to be pivotally connected to the crank shaft and adapted to be manually drawn or swung in an arc parallel to the track rails whereby said arm can be rotated 10 in reverse directions for the purposes specified.

5 crank shaft suitably journaled and operatively connected to said swivel block, and a switch throwing lever mounted on said

OLIVER WILSON.
